(57) **CLAIM**

The ornamental design for an eyeglasses hinge, as shown and described.

DESCRIPTION

FIG. 1 is a top, rear perspective view of an implementation of eyeglasses having two hinges, each of the two hinges having the same design but oriented opposite to one another; FIG. 2 is top, right side perspective view of the left hinge of the eyeglasses of FIG. 1;

FIG. 3 is top, right side perspective view of the right hinge of the eyeglasses of FIG. 1;

FIG. 4 is a top, left side perspective view of the right hinge of FIG. 1;

FIG. 5 is a top, left side perspective view of the left hinge of FIG. 1;

FIG. 6 is a right side view of one of the hinges;

FIG. 7 is a left side view of one of the hinges;

FIG. 8 is a rear view of one of the hinges;

FIG. 9 is a front view of one of the hinges; and,

FIG. 10 is a top view of one of the hinges, the bottom view being a mirror image.

The broken lines shown in the drawings are included for the purpose of illustrating environmental subject matter that forms no part of the claimed design.

The dot-dash lines represent bounds of the claim and form no part of the claimed design.

1 Claim, 4 Drawing Sheets
